UNITED STATES PATENT OFFICE.

COLE STICKLE, OF INDIANAPOLIS, INDIANA.

ELECTRICAL CONTROL FOR PAPER-MAKING MACHINES.

1,213,968.

Specification of Letters Patent. Patented Jan. 30, 1917.

Application filed November 8, 1915. Serial No. 60,424.

To all whom it may concern:

Be it known that I, COLE STICKLE, a citizen of the United States, and a resident of Indianapolis, county of Marion, and State of Indiana, have invented a certain new and useful Electrical Control for Paper-Making Machines; and I do hereby declare that the following is a full, clear, and exact description thereof, reference being had to the accompanying drawings, in which like letters refer to like parts.

The object of this invention is to control the heat supply to the cylinders of a paper making machine or any like machine, by the tension of the sheet of paper or other sheet going through the machine, as said tension is changed by changes in the moisture of the sheet. When the sheet becomes relatively dry it will shorten, and through means, such as herein indicated, will reduce or shut off the heat supply to the cylinders until the heat imparted to the sheet is reduced so that the sheet will not be too dry. When the heat is reduced and the sheet becomes too moist it will lengthen relatively and through the means, as herein indicated, will control the heat supply so as to increase the heat and dry the paper more. In this way, the sheet of paper or other material, as the tension changes through changes in moisture, will automatically regulate the heat for drying the sheet.

This invention is not limited to any particular means for carrying out this object. That shown herein consists of an electric switch with mechanism acted upon by the sheet of paper or the like, as it passes over the cylinders and through the machine, so that when the sheet becomes relatively dry, it will shorten and close the circuit and through an intermediate electrical apparatus close the valve in the heating apparatus so as to reduce or cut off the supply of heat to the cylinders. When the heat is not sufficient to dry the sheet, its moist condition will somewhat lengthen the sheet so that the electrical contact switch will open the circuit and through intermediate means cause the valve to open and admit more heat.

The full nature of the invention will be understood from the accompanying drawings and the following description and claims.

In the drawings, Figure 1 is a side elevation of a portion of the paper making machine equipped with said invention, parts

being broken away. Fig. 2 is a horizontal section through a part of the machine on the line 2—2 of Fig. 1. Fig. 3 is an end elevation of the electrical switch mechanism and two adjacent cylinders, showing the parts in position when the sheet of paper has become moist and has caused the valve for controlling the heat to open, parts being broken away. Fig. 4 is substantially the same showing the parts in position when the sheet has become dry and has closed the circuit for the purpose of closing the valve to reduce the heat.

There is shown herein a paper making machine having a frame 10 and hollow drying cylinders 11 over which a sheet of paper 12 passes through the machine. The sheet of paper is dried by steam being introduced into said cylinders through individual pipes 13 leading from the header 14. The live steam comes in under high pressure through a high pressure pipe 15. A reduction valve mechanism 16 is provided for reducing the pressure of the steam as it enters the header. The reducing valve mechanism 16 is controlled by water under pressure passing thereto through a by-pass pipe 17 from a high pressure water pipe 18. The details of the construction of the reducing valve mechanism 16 are not shown as it is of common type, but it is so arranged that when the water under pressure passes through pipe 17 the valve will tend to close and when the water under pressure is shut off from passing through pipe 17, the valve will be open. The passage of water under pressure from the high pressure pipe 18 to the by-pass 17 is controlled by an auxiliary valve 19 which is opened by a solenoid 20 in a magnet 21 when it is energized by the current passing through lines 22 and 23. Current comes to this machine over a main line 24 and branch 25 to an electrical switch controlled by a sheet of paper and hereafter explained and through said switch passes to line 22 and goes out over line 23 and through a line 26. There is a shunt line 27 having an indicating lamp 28 to indicate whether the valve controlling circuit is open or closed. The means whereby the sheet of paper controls said valve closing circuit is illustrated in Figs. 2, 3 and 4. There is a bearing sleeve 30 carried by a bracket 42 secured to the upright frame member 10 by screws 31 and the same construction is on the opposite side of the machine and in the

- sleeves 30 a rod 32 is mounted so as to oscillate and it carries a radially extending arm 33 rigidly connected therewith at each end of a cylinder 11 and the outer ends of said arms carry a loose roller 35 which extends transversely of the machine below and to the front of said cylinder and bears against the inner surface of the sheet 12 as it travels over said cylinder.
- 10 On one end of said rod 32 a contact arm 36 is rigidly secured between its ends. The short end of said contact arm 36 operates between two stop screws 37 in ears 38 connected with the frame 10 so as to limit the 15 oscillation of the arm 36. The long end of said arm 36 carries an adjustable contact 39 adapted to coöperate with a contact 40 adjustably mounted on a rigid arm 41 secured to said bracket 42.
- 20 The arms 33 extend upwardly and rearwardly from the rod 32, as shown in Figs. 3 and 4, so that their weight and the weight of the roller 35 will tend to move the contact arm 36 by gravity down to the open position 25 shown in Fig. 3, and thus open the circuit whenever the sheet of paper has become slack enough by being too moist and allows such action. When that happens and the circuit is open, the magnet 21 is not energized and, therefore, the solenoid 20 drops 30 and causes the closing of the valve 19 which shuts off the water under pressure passing through pipe 17 for holding the reducing valve at 16 in closing or reducing position 35 and that opens the reducing valve and admits more steam or heat to the cylinders so as to impart more heat to them and dry the paper better. If, on the other hand, the sheet of paper has become relatively dry, it 40 shortens or takes up its slack, as indicated in Fig. 4, and moves the roller 35, arms 33, rod 32 and contact arm 36 so as to close the circuit and when the circuit is closed the magnet 21 will be energized, the solenoid 45 elevated, the auxiliary valve 19 opened and water under pressure will pass through pipe 17 and move the reducing valve to a position for decreasing the supply of heat to the cylinders.
- 45 The invention is not limited to the particular switch means shown or to the valve arrangement, as it consists in utilizing the change in the slackness or tautness of the sheet of paper or other sheet for, through 50 suitable intermediate mechanism, controlling the reducing valve or other valve which controls the heat supply. The other parts of the mechanism shown herein and not described are of well-known construction and 55 nature and are not fully explained here as they do not constitute any essential part of this invention.
- The invention claimed is:
1. The combination of cylinders for drying a sheet of paper or the like, means for 60 heating said cylinders, electrical means for regulating said heating means, and means controlled by the tension of a sheet of paper or the like as it passes over said cylinders for operating said electrical heat regulating 65 means.
2. The combination with cylinders for drying a sheet of paper or the like, means for heating said cylinders, and a valve for controlling the heat of said cylinders, of means moved by the sheet of paper or the like passing over said cylinders according to its condition of moisture and dryness, an electric switch operated by said means, an electric circuit opened and closed by said switch, and electrical means controlled by said circuit for causing the regulation of the heat controlling valve.
3. The combination with cylinders for drying a sheet of paper or the like, means for 70 heating said cylinders, and a valve for controlling the heat of said cylinders, of a main frame for supporting said cylinders, a frame mounted on said main frame near one of said cylinders so as to rock and having a roller on it extending transversely of the machine so as to bear against the sheet of paper or the like, and arranged so that said sheet as it tightens from dryness will rock said frame in one direction and when it slacks from 75 moisture will permit the frame to rock in the opposite direction, a contact arm secured to said main frame, an adjustable contact on said arm, a contact arm secured to said rocking frame, a contact in said movable arm adapted to be moved against and away from the other contact as the rocking frame is moved in one direction or the other, an electric circuit opened and closed by said switch, and electrical means controlled by 80 said circuit for causing the regulation of the heat controlling valve.
4. The combination with cylinders for drying a sheet of paper or the like, means for 85 heating said cylinders, and a valve for controlling the heat of said cylinders, of a main frame for supporting said cylinders, a frame mounted on said main frame near one of said cylinders so as to rock and having a roller 90 on it extending transversely of the machine so as to bear against the sheet of paper or the like, and arranged so that said sheet as it tightens from dryness will rock said frame in one direction and when it slacks from moisture will permit the frame to rock in the opposite direction, a contact arm secured to said main frame, an adjustable contact on said arm, a contact arm secured to said rocking frame, a contact in said movable arm 95 adapted to be moved against and away from the other contact as the rocking frame is moved in one direction or the other, an electric circuit opened and closed by said switch, and electrical means controlled by 100 said circuit for causing the regulation of the heat controlling valve.
5. The combination with cylinders for drying a sheet of paper or the like, means for 105 heating said cylinders, and a valve for controlling the heat of said cylinders, of a main frame for supporting said cylinders, a frame mounted on said main frame near one of said cylinders so as to rock and having a roller 110 on it extending transversely of the machine so as to bear against the sheet of paper or the like, and arranged so that said sheet as it tightens from dryness will rock said frame in one direction and when it slacks from moisture will permit the frame to rock in the opposite direction, a contact arm secured to said main frame, an adjustable contact on said arm, a contact arm secured to said rocking frame, a contact in said movable arm 115 adapted to be moved against and away from the other contact as the rocking frame is moved in one direction or the other, means for limiting the movement of said movable arm, an electric circuit opened and closed by said switch, and electrical means controlled 120 by said circuit for causing the regulation of the heat controlling valve.

by said circuit for causing the regulation of the heat controlling valve.

5. The combination with cylinders for drying a sheet of paper or the like, of means for heating said cylinders, a valve for controlling the heat of said cylinders, electrically operated means for regulating said valve, an electrical circuit for energizing said electrical means, a switch for opening and closing said circuit, and means controlled by the tension of the sheet of paper or the like as it passes over said cylinders for operating said switch.

10 6. The combination of cylinders for drying a sheet of paper or the like, means for heating said cylinders, a valve for controlling said heating means, an auxiliary valve for controlling said heat controlling valve, and means controlled by the tension of a 15 sheet of paper or the like as it passes over said cylinders for controlling the auxiliary valve.

7. The combination of cylinders for drying a sheet of paper or the like, means for heating said cylinders, a reducing valve for controlling said heating means, an auxiliary valve for controlling said heat controlling valve, and means controlled by the tension of a sheet of paper or the like as it passes over said cylinders for controlling the auxiliary valve.

8. The combination of cylinders for drying a sheet of paper or the like, means for heating said cylinders, a valve for controlling said heating means, an auxiliary valve for controlling said heat controlling valve, and an electrical means controlled by the tension of a sheet of paper or the like as it passes over said cylinders for operating said auxiliary valve.

In witness whereof, I have hereunto affixed my signature.

COLE STICKLE.
